RADIO TELEPHONE & TELEGRAPH CO., OF JERSEY CITY, NEW JERSEY, A CORPORA-
TION OF DELAWARE

ELECTRON DISCHARGE DEVICE

No Drawing. Application filed March 1, 1924. Serial No. 696,396.

This invention relates to electron discharge devices and more particularly to the means by which the same are exhausted.

The objects of the invention are to enable 5 an electron discharge device to be manufactured in less time than heretofore; to reduce the time and expense involved in obtaining a high degree of evacuation of the device; to employ a chemical clean up agency for obtaining 10 part of the evacuation; to employ a "flash" as well as a chemical clean up agency; to employ a chemical clean up agency and flash adapted to be applied simultaneously and put into effect at different 15 times; to enable the chemical clean up agency and flash to be put into effect by use of high frequency or by plate bombardment; to obtain an improved method of manufacture; to secure 20 simplicity of construction and operation, and to obtain other advantages and results as may be brought out in the following description.

In the manufacture of electron discharge devices, it has become more or less common 25 practice to employ a filament which includes the element thorium as the emissive substance. Thorium oxidizes quite readily and consequently the filament as inserted in an electron discharge device contains exposed 30 portions of thorium oxide rather than pure thorium. In order to reduce thorium oxide to thorium, it has become common practice to employ a flash of some suitable material, of which magnesium is the one most generally 35 used. The operation is ordinarily carried out by applying a small portion of magnesium to the plate and then after the tube is evacuated as much as possible by the pump, the plate is heated to a point where the 40 magnesium will flash and the resulting vapor will operate to reduce the thorium oxide to thorium. The present invention contemplates means for first obtaining a partial vacuum by means of a pump so as to materially 45 reduce the time during which the electron discharge device has to be connected with the pump for the purpose of evacuation, and then high evacuation is obtained by other means, after which the magnesium or other material may be flashed similar to the

manner in which that operation has been carried on heretofore. In order to obtain the high vacuum by means other than by pumping, I employ a chemical which is flashed similar to the magnesium, preferably before 55 the magnesium is flashed, said chemical obtaining a high state of evacuation of the tube by means of reduction of the residual gases within the tube. The magnesium could not be used practically for this purpose, both 60 because it is not sufficiently active to reduce the residual gases to the necessary amount nor is it practical to flash the magnesium until a very much higher degree of eva- 65 cuation has been effected than is required in connection with the present invention.

I preferably employ in combination with a flash of magnesium or other suitable material, chemical clean up agency of phosphorus. The advantage of employing phosphorus is 70 that it may be flashed at a lower temperature than magnesium and also that phosphorus will effectively reduce the residual gases when flashed while the device is not in such a high state of evacuation as necessary to obtain reduction by means of magnesium. I may also state, that very good results are obtained by use of red or amorphous phosphorus. Since phosphorus in this state is much more convenient to handle and does not have to be 75 protected until ready to be flashed, it is the 80 better variety to use.

In order to apply the phosphorus to the plate or other part from which it is to be flashed, I preferably mix the phosphorus and magnesium in the nature of a paste or paint and apply it with a brush or in any other suitable manner. As much of the plate as desired may be covered with the mixture, although it will probably be sufficient in most 85 cases to employ only a good sized spot on the plate. I do not wish it to be understood that it is necessary to mix the phosphorus and magnesium, and indeed, in some instances, it may be highly desirable not to mix the two. 90

The flashing of the phosphorus and magnesium, as indicated above, takes place at different times, phosphorus being flashed first in order to reduce the residual gases and obtain a higher degree of evacuation, after 100

which the magnesium is flashed in order to reduce the thorium oxide of the filament to thorium. There are a number of ways of obtaining the flash of the phosphorus and magnesium, one instance of which is the usual method of plate bombardment. The temperature of the plate is raised by means of an initial electron emission to such a point as to cause the phosphorus to vaporize and combine with the residual gases. Continued bombardment of the plate will raise the temperature to a higher degree and thus obtain a subsequent flashing of the magnesium. The flashing of magnesium has heretofore been effected by means of high frequency current, and this may also be utilized for flashing the phosphorus. In order to obtain a marked time difference between the flashing of the phosphorus and magnesium, the phosphorus may be applied to the plate toward one end of the electron discharge device and the magnesium applied to the plate toward the other end, so that the high frequency coil may be manipulated to operate only on the end of the plate to which the phosphorus is applied, so as to flash the phosphorus and then moved along so as to operate upon the other end of the plate and flash the magnesium. It is apparent that both the phosphorus and the magnesium provide clean up agents both of which are flashed but at different temperatures. In the broad aspect of this invention any two suitable agents could be used which are adapted to be flashed at different temperatures. The term "flash", as used in the claims, relates to the clean up agent adapted to be activated at the higher temperature.

Obviously other detail changes and modifications may be made in the manufacture and use of my improved electron discharge device, and I do not wish to be understood as limiting myself to the exact structure or method described, except as set forth in the following claims when construed in the light of the prior art.

Having thus described my invention, I claim:

1. An electron discharge device having applied thereto in the course of manufacture a mixture of phosphorus and magnesium.
2. A method of manufacturing electron discharge devices consisting in applying a mixture of a chemical clean up agency and a flash to the plate, and flashing the chemical clean up agency and flash at different times.
3. A method of manufacturing electron discharge devices consisting in applying a mixture of a chemical clean up agency and a flash to the plate, and flashing the chemical clean up agency and subsequently flashing the flash.
4. In an electron discharge device the combination of a filament containing thorium, a plate electrode having thereon a clean-up

agent containing phosphorus and a flash material having a higher flashing temperature than the clean-up agent to activate the filament after the attainment of a high degree of evacuation by the clean-up agent.

5. An electron discharge device having an electron emitting filament containing thorium a magnesium filament activating flash and a clean-up agent on the interior of said device, the clean-up agent being rendered effective prior to the activation of said flash for reducing the vacuum in said device to a point requisite for the proper action of said flash.

6. An electron discharge device according to claim 5 in which said clean-up agent includes phosphorus.

7. An electron discharge device having a thoriated filament, a flash material containing magnesium for activating said filament and a clean-up agent effective to clean up the gases within said device prior to the activation of said flash.

8. The method of manufacturing an electron discharge device having a thoriated electron emitting filament which comprises applying a chemical clean-up agent and a filament activating flash material on the interior of the device, and flashing the clean-up agent prior to the flashing of the filament flash material.

9. The method of manufacturing an electron discharge device having a thoriated electron emitting filament consisting in applying a chemical clean-up agent and a magnesium filament activating flash to the plate, flashing the clean-up agent to reduce the evacuation to a point where the filament flash will be effective and then flashing the flash.

10. The method of manufacturing thoriated filament electron discharge devices employing phosphorus and magnesium for evacuation which comprises first flashing the phosphorus to reduce the evacuation to a point where the magnesium can be effectively flashed to activate the filament, and then flashing the magnesium to activate the filament.

11. The process of exhausting electron discharge devices having thoriated electron emitting filaments which includes the step of bringing the plate to one temperature to render a clean-up agent effective, and subsequently bringing the plate to a higher temperature to activate a filament activating flash material.

12. The process of exhausting an electron discharge device of the thoriated filament type employing a chemical clean-up agent and a magnesium flash on the plate which comprises bringing the plate to one temperature to activate the clean-up agent, and subsequently raising the temperature of the plate when the requisite degree of vacuum has been attained to flash said magnesium to activate the filament.

13. An electron discharge device having an electron emitting member in the form of a thoriated filament a plate having applied thereto a clean-up agent containing phosphorus, and a magnesium filament activating flash, and means including said emitting member for bringing said plate to one temperature to render said clean-up agent effective and for subsequently raising the temperature of said plate to flash said magnesium to activate the filament.

14. An electron discharge device of the thoriated filament type having a chemical clean-up agent of amorphous phosphorus, and a filament activating flash material of magnesium.

15. An electron discharge device having an electron emitting filament containing thorium, said device having applied thereto in the course of manufacture a mixture of a chemical clean-up agent containing phosphorus, and magnesium for activating the thoriated filament.
